UNITED STATES PATENT OFFICE.

WILLIAM LINEHAN, OF CHICAGO, ILLINOIS.

DEVICE FOR FEEDING FLUID INTO BOILERS TO PREVENT INCrustATION.

SPECIFICATION forming part of Letters Patent No. 225,622, dated March 16, 1880.

Application filed September 22, 1879.

To all whom it may concern:

Be it known that I, WILLIAM LINEHAN, of Chicago, in the county of Cook and State of Illinois, have invented a new and Improved 5 Device for Feeding Fluid into Steam-Boilers to Prevent Incrustation, of which the following is a specification.

The object of this invention is to furnish a device for automatically feeding the fluid for preventing incrustation into the boiler along with the feed-water, when supplied by a pump or an injector.

It consists of a reservoir for holding the fluid, from the bottom whereof a siphon-pipe leads 15 to the pump-barrel or injector at a point where the water is forced or drawn by suction into the boiler. The said siphon-pipe is supplied with a stop-cock and check-valve, to regulate the amount supplied and to prevent back-press- 20 ure when pumping.

In the accompanying drawings, Figure 1 is a plan of my improvement. Fig. 2 is a longitudinal vertical section of the same, taken on line *x x* of Fig. 1; and Fig. 3 shows it applied 25 to a pump-barrel.

Similar letters of reference indicate corresponding parts.

Referring to the drawings, A represents the fluid-reservoir, provided with a circular strainer, *a*. From the bottom of this reservoir a pipe, B, leads to a valve-chamber, *b*, in which is seated a puppet check-valve, *c*. This valve-chamber is on a level with the bottom of reservoir A, and from it extends a tube, *b'*, with 30 a valve-chamber, *C*, connected with it, provided with a conical valve, *d*, seated in the diaphragm *e*. The stem of this valve projects out through a stuffing-box, *e'*, and is provided with a hand-wheel, *f*, for operating said valve 35 *d*. From valve-chamber C a tube, *g*, extends, for connecting the device with the pump-barrel or injector, as the case may be.

The device is applied as follows: In Fig. 3 it is shown applied to a pump, C', (illustrated 40 in dotted lines.) The tube *g* is connected with the pump-barrel D anywhere between the suc- 45 tion-valve D' and discharge-valve E. The stop-cock or valve *d* is lifted off its seat suffi-

ciently far to allow the proper quantity of the fluid to pass from the reservoir A into the 50 boiler. The fluid is put in reservoir A, and passes down through pipe B, through valve *c*, thence through the tube *b'*, valve-chamber C, to tube *g*, and from this tube *g* it enters the pump-barrel D. When the pump is drawing 55 it lifts check-valve *c* from its seat, which permits the fluid to flow through to the pump-barrel; but on the return stroke it closes the check-valve *c*, thus preventing back-pressure in the feeding device, and the fluid that flows 60 out on the suction stroke, mingling with the water, is forced through valve E, and thence, through discharge-pipe F, into the boiler. Thus at every suction stroke of the pump a certain quantity (regulated by stop-cock *d*) is 65 permitted to flow into the pump-barrel D, and on the return stroke it is forced into the boiler.

By this arrangement a small but sufficient quantity of the anti-incrustation fluid is regularly and automatically fed to the boiler, preventing waste and acting with better effect 70 than when forced directly into the boiler in quantities.

The device is equally applicable to an injector. When used with injectors it is attached 75 on the suction side.

I do not confine myself to the arrangement of stop-cock and check-valve shown and described herewith, as other arrangements for producing the same effects may be adopted 80 without departing from my invention.

Having thus described my invention, I claim as new and desire to secure by Letters Patent—

The combination, with tube *g*, leading to 85 pump-barrel, of the reservoir A, the piping B, the chamber *b*, having valve *c*, and placed on a level with the bottom of reservoir A, and the chamber C, connected by tube *b'* with chamber *b*, and provided with valve *d*, all constructed 90 and arranged as shown, and for the purpose specified.

WILLIAM LINEHAN.
